CLAIM

The ornamental design for a high efficiency twisted leaf ceiling fan, as shown and described.

DESCRIPTION

FIG. 1 is a bottom perspective view of a ceiling fan with the above novel twisted blades.

FIG. 2 is a top perspective view of the ceiling fan with novel blades of FIG. 1.

FIG. 3 is a side perspective view of the ceiling fan with novel blades of FIG. 1.

FIG. 4 is a bottom view of the ceiling fan with novel blades of FIG. 1; and,

FIG. 5 is a top view of the ceiling fan with novel blades of FIG. 1.

The broken lines showing mounting holes in FIGS. 1-5 are for illustrative purposes and form no part of the claimed design, and the broken lines showing a ceiling mounting cap, motor housing, canopy and pull chain in FIGS. 1-5 are for illustrative purposes and form no part of the claimed design.
